W. L. SCOTT

GAS ENGINE FUEL ECONOMIZER

Filed Aug. 16, 1920

William Lester Scott.

Harry O. Schroeder
attorney

Patented Sept. 15, 1925.

UNITED STATES PATENT OFFICE.

WILLIAM LESTER SCOTT, OF OAKLAND, CALIFORNIA.

GAS-ENGINE FUEL ECONOMIZER.

Application filed August 16, 1920. Serial No. 403,895.

To all whom it may concern:

Be it known that I, WILLIAM LESTER SCOTT, a citizen of the United States, residing at Oakland, in the county of Alameda and State of California, have invented certain new and useful Improvements in Gas-Engine Fuel Economizers, of which the following is a specification.

My invention is a gas engine fuel economizer.

My invention is illustrated in the annexed drawing which forms a part of this specification.

Referring to the drawing:

15 Figure 1 is a side elevation of my invention applied to a gas engine.

Figure 2 is a vertical section of the vaporizer.

20 Figure 3 is a vertical section of my invention omitting the vaporizer.

Figure 4 is a side view of the heater.

Figure 5 is an end view of the same.

25 Figure 6 is a section on the line 6—6 of Figure 5.

30 In the drawing, 1 indicates a vertical cylindrical tube, the lower end of which being open and extending into the sump opening 2 in the forward end of a gas engine casing. Said tube has an external bead 3 near its lower end in which is supported

35 a screen 4, said bead being adapted to rest upon the edge of the sump opening to support the tube at the proper elevation. A head 5 is detachably fitted in the upper end 40 of the tube 1, in which head is an intake valve 6 normally closed by a spring 7 which surrounds a screw 8 extending through and seated in said head, the ends of the spring bearing against the valve and a head 9 on

45 the lower end of the screw. The valve 6 may be regulated by the set screw 8. A horizontal tube 10 extends from the vertical tube 1, said tubes being of metal and integral. A flexible tube 11 connects to the

50 end of the tube 10 and to the air inlet of the engine carbureter 12. A vaporizer 13 is mounted on the exhaust manifold 14 of the gas engine. The top wall 15 of the vaporizer has a threaded opening 16 in which

55 is screwed the upper enlarged threaded end of an air inlet tube 17 which extends downwardly to a point near the bottom of the vaporizer. A cup-shaped air heater 18 is secured to the outside of the exhaust manifold 14 by a screw stud 19 which extends from a transverse partition 20 in the heater

and screws into the outer wall of said manifold. The partition 20 divides the heater into two compartments 21 and 22, the compartment 21 resting adjacent the exhaust manifold 14 whereby the air in said compartment is heated. Air inlets 23 are provided in the wall of the compartment 21 for the admission of air from the atmosphere therein, and ports 24 are provided in the partition 20 for the passage of the heated air from the compartment 21 into the compartment 22. A tube 25 leads from the compartment 22 and its outer end is inserted in the outer end of the vaporizer inlet tube 17 for the admission of heated air from the heater 18 into the vaporizer 13.

20 A tube 26 is connected at one end to the top of the vaporizer by a union 27 and at its other end to the tube 10 by a union 28, one member of the union 27 screwing into a threaded opening 29 in the top wall 15 of the vaporizer, and a threaded nipple 30 on the pipe 10 forming one member of the union 28. A screening disk 31, preferably of felt is placed in the inner end of the member of the union 27 which screws into the opening 29 in the top of the vaporizer, said disk serving to screen the water vapor passing from the vaporizer through the tube 26 into the tube 10.

Heated air and oil gas is taken into the carbureter 12 from the engine crank case through the tube 1, tube 10 and tube 11, the screen 4 screening said air and gas; while water vapor at the same time is taken into the carbureter through tubes 26, 10 and 11 from the vaporizer 13, which contains water, through which heated fresh air passes from the heater 18 and tube 25 through tube 17, before entering the tube 26, the vaporizer being heated by the exhaust manifold 14. If the engine requires more air than under normal conditions, the valve 6 automatically opens and admits air into the tube 1 which passes through tubes 10 and 11 into the carbureter 12.

Having described my invention, I claim:

1. In a fuel economizer for use with internal combustion engines, a T-shaped pipe fitting for connection with the breather pipe of said engine having a short vertical section with openings at each end and a horizontal section connection therewith, the lower end of the vertical section slidably fitting within the breather pipe and having a bead to limit its downward movement

- within the breather pipe, a screen supported within said vertical section at the beaded portion thereof, a cap for closing the opposite opening of said vertical section having an air admission port, an adjustable spring controlled valve carried by said cap for regulating the admission of air into said economizer, a tube adapted to connect the horizontal section of said fitting with the air intake portion of the carburetor of said engine, said horizontal section constituting a suction pipe whereby oil vapor and heated air are drawn from the crank case, a water vaporizer mounted so as to be heated by said engine, and a water vapor outlet pipe for said vaporizer connected to the horizontal connection of said fitting.
2. In a device of the class described, a T-shaped pipe fitting having one end adapted to slidably fit within the breather pipe of an internal combustion engine so as to support said fitting, means formed on said fitting for limiting the sliding movement of the fitting within said breather pipe, a tube adapted to connect the breather pipe with the intake of the carburetor of said engine so that a partial vacuum is maintained within the crank case during the operation of said engine, a valve supported by said fitting for affording atmospheric connection for said fitting when desired, means supported by the motor for producing water vapor and connecting means between said water vaporizing means and said pipe fitting.
3. In a device of the class described, a T-shaped pipe fitting having one end adapted to fit within the breather pipe of an internal combustion engine, a tube adapted to connect the breather pipe with the intake of the carburetor of said engine so that a partial vacuum may be maintained within the crankcase during the operation of the engine, a valve supported by said fitting for affording atmospheric connection for said fitting, spring means whereby said valve is normally held closed, said valve being automatically opened when the difference between atmospheric pressure and the pressure within the fitting exceeds the tension of said spring, means whereby the tension of said spring may be adjusted, means supported by the motor for producing water vapor and connecting means between the water vaporizing means and said pipe fitting.
4. In an internal combustion engine including a carburetor and a breather pipe connected with the crank case: a fuel economizer affording a connection between the breather pipe and the carburetor, said economizer being adapted to slidably fit within the breather pipe so as to be supported thereby, means to limit the sliding movement of said economizer within said breather pipe, adjustable means for controlling the amount of air passing through said economizer to the carburetor, means connected to the engine for producing water vapor, and a conductor connecting said vapor producing means with said economizer, said economizer constituting an extension of the air suction pipe of the carburetor whereby oil vapor and heated air are drawn from the crank case and water vapor is caused to be mixed therewith as said oil vapor and heated air passes through the carburetor.

In testimony whereof I affix my signature.

WILLIAM LESTER SCOTT.
